SAMUEL TROOD, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

CURLING-IRON.

1,210,018.

Specification of Letters Patent.

Patented Dec. 26, 1916.

Application filed February 4, 1913. Serial No. 746,218.

To all whom it may concern:

Be it known that I, SAMUEL TROOD, a citizen of the United States, and a resident of Edgewood Park, in the county of Allegheny and State of Pennsylvania, have invented a new and useful Improvement in Curling-Irons, of which the following is a specification.

My invention relates to electrical heating devices, and it has special reference to electrically-heated curling irons.

The object of my invention is to provide a curling iron embodying a resiliently supported heater element for preventing breakage, and a swiveling attachment whereby the iron may be rotated with respect to the supply conductors, without interrupting the circuit, for preventing kinking and rapid wearing of said conductors.

Heretofore, curling irons have been constructed with the heating portion and supply conductors mutually stationary and with rigid support of the element. This entailed a constant kinking and rapid wearing of the conductors, as will be readily understood; likewise, the probability of breakage of the heating element when the iron was subjected to jars, was great.

According to my present invention, the above-mentioned objectionable features are removed by reason of a swiveling concentrically-disposed plug-and-socket connector and a resiliently-supported heater element, as hereinafter described.

In the accompanying drawing, Figure 1 is a view, partially in longitudinal section and partially in elevation, with parts broken away, of a curling iron embodying my invention; Fig. 2 is an enlarged longitudinal section, with parts broken away, of the plug-connector and the heater embodied in my invention; Fig. 3 is a view, in elevation, of the socket portion of the connector shown in Fig. 1; Fig. 4 is a view, in section, on the line IV-IV of Fig. 1; and Figs. 5 and 6 are views, in section, taken similarly on the lines V-V and VI-VI, respectively.

Referring to the drawing, a curling iron 1 comprises a heater 2, a cylindrical shell 3 incasing the heater 2, a pivotally mounted tong 4 fitting over the shell 3, a handle 5 supporting one end of said shell, an auxiliary handle member 6, and a plug-and-socket connector 7 disposed within the handle 5.

The heater 2 comprises a centrally dis-

posed rod 8, a layer of suitable insulating material 9 disposed around said rod, a plurality of convolutions of conductor 10 wound around the material 9, and an outer protective covering 11. It is understood that said conductor may be embedded in cement, in which case no covering is necessary. The incasing shell 3 fits within a ferrule 12 on the handle 5 and is provided with a button 13 for closing the outer end. The tong 4 is well-known in the art and consequently need not be further described. The handle 5 comprises a main body portion 14 and a thin-walled shell 15 projecting beyond the outer end of said body portion and adapted to contain the plug-and-socket connector 7, as hereinafter described. An axially-disposed recess 16 extends through the body portion 14 and is lined with a metal shell 17. The rod 8 is connected to one end of the heater conductor 10 and extends within the hollow shell 15 for forming one terminal member 18, which is provided with a cupped end 20. A second terminal member 19 consists of a tube insulated from and concentrically disposed around the rod 8 near its free end. The said tube has a bulb-shaped end 22 that is adapted to engage a tubular clip 25, as hereinafter described. (See Fig. 2.)

The auxiliary handle member 6 is of insulating material and tubular in form, and comprises two portions, an outer portion 6^a, adapted to be held in the hand and into which supply conductors 23 and 24 extend, and a portion 6^b, which screws into the portion 6^a and is adapted to fit loosely within the shell 15 of the handle 5, and acts as a guiding member for the connector 7.

The terminals 18 and 19 comprise the plug portion of the connector 7, and the main socket portion comprises a tubular clip 25, of substantially bottle-shape, provided with a plurality of longitudinal slots 26 to lend resiliency thereto. A ring 27 is attached to the unslotted end of the clip 25 and has an integral arm 28 to which the supply conductor 23 is connected by a screw 29. A centrally disposed rod 30 is rigidly supported and insulated from the ring 27 by insulating disks 31 and engages the cupped end 20 of the terminal 18. A metal strip 32 serves to connect the outer end of the rod 30 to the second supply conductor 24 by a screw 33.

2
A spring 34 is disposed at the outer end of the incasing shell 3 upon the button 13 to coöperate with the clip 25 to resiliently support the heater element 2, thus relieving the thrust on said element. The shell 17 lining the recess 16 in the handle 5, acts as a resilient guide for the terminals 18 and 19 by reason of having a plurality of fingers 35 cut from the walls near the outer end and bent inwardly to engage the terminal member 19.

10 The adaptability of the curling iron to rotative movement with respect to the auxiliary handle member 6 will be understood 15 from the foregoing description.

15 In using the curling iron, the auxiliary handle member 6 may be held stationary, and the iron turned between the thumb and forefinger, thus facilitating the process of 20 hair-curling. During the rotative movement, the bulb-shaped end of the terminal 25 19 may turn within the clip 25, and the rod 30 may turn within the cupped end 20 of the terminal 18, thereby keeping the electrical circuit intact.

25 I do not wish to be restricted to the specific structure and details herein set forth, but desire that only such limitations shall be imposed as are indicated in the appended 30 claims.

35 I claim as my invention:

1. In an electric apparatus, the combination 40 with an electrically-heated implement, of an auxiliary member rotatably associated with the said implement and a plurality of rotatably engaging contact members 35 enclosed within the said auxiliary member.

2. An electrically-heated implement comprising a resiliently-supported heating element, and concentrically disposed resilient means for making electrical connections thereto and permitting movement of said element with respect to said resilient means.

3. An electrically-heated implement comprising a resiliently-supported heating element, and concentrically-disposed resilient means for detachably making electrical connections thereto and permitting rotative movement of said element with respect to 45 said resilient means without interruption of the circuit.

4. In a heating apparatus, the combination 55 with an electric heater element and a supporting handle therefor, of a movable auxiliary member, and resilient means 50 enclosed within the said auxiliary member for making electrical connections to said heater element and permitting movement thereof with respect to said handle member.

5. In a heating apparatus, the combination 60 with an electric heater element and a supporting handle therefor, of a rotatable auxiliary member, and concentrically-disposed resilient means associated with said auxiliary member for detachably making

electrical connections to said heater element and permitting rotative movement thereof with respect to said auxiliary member without interruption of the circuit.

6. In a heating apparatus, the combination 70 with an electric heater element and a supporting handle therefor, of a rotatable auxiliary member, and a two-part concentrically-disposed resilient plug-and-socket electrical connector adapted to permit swiveling of said heater element therein.

7. In a heating apparatus, the combination 75 with an electric heater element, an incasing member and a supporting handle therefor, of an auxiliary relatively movable member, means associated with said incasing member for resiliently supporting said element, and a resilient plug-and-socket connector concentrically disposed in said auxiliary member for making electrical connections 80 to said element.

8. In an electric heating device, the combination 85 with a heater element, of a centrally-disposed plug-and-socket connector therefor comprising a centrally located pair of relatively movable butt contact members, a tubular plug and a coöperating resilient socket detachably inclosing said members, and insulated therefrom.

9. An electric heating device embodying 95 a tubular shell, a heater longitudinally disposed therein, and resilient means for holding said heater centrally within said shell including a resilient member embracing one end of the said heater.

100 10. An electric heating device embodying a tubular shell, a heater longitudinally disposed therein, a supporting handle, resilient means located in one end of said shell for support of said heater in a longitudinal direction, and means associated with said handle for resiliently and centrally holding said heater in position.

11. An electric device embodying a heater comprising a centrally disposed conducting 110 rod and a heater element associated therewith and embedded in insulating material, and resilient means associated with said heater for preventing breakage thereof including a resilient member embracing one 115 end of the said heater.

12. An electrically-heated implement embodying a swiveling connecting device comprising a plurality of pairs of concentrically disposed contact members, at least one 120 of each pair of contact members being resilient.

13. An electrically-heated device embodying a heater provided with a centrally disposed conducting rod projecting outwardly 125 to form a terminal, a tubular shell surrounding and insulated from said rod and adapted to form another terminal, and detachable coöperating contact members for severally engaging said rod and said shell.

14. In a heating apparatus, the combination with an electric heater, of a supporting handle having an end recess, and an auxiliary member extending into said recess and adapted to permit rotative movement of said supporting handle.

15. In a heating apparatus, the combination with an electric heater element, of a supporting handle having an outer end recess, an auxiliary member extending into said recess, and means associated with said element and said auxiliary handle for effecting electrical connections to said element and for permitting rotative movement of said supporting handle with respect to said auxiliary handle.

16. An electrically heated implement comprising a heating element and concentrically disposed overlapping means for making re-

silent electrical connections thereto and permitting movement of the said element with respect to the said resilient means. 20

17. An electrically heated implement comprising a heating element and concentrically disposed overlapping means for detachably 25 and resiliently making electrical connections thereto and permitting rotative movement of the said element with respect to the said resilient means without interruption of the circuit.

In testimony whereof, I have hereunto subscribed my name this 23rd day of January, 1913.

SAMUEL TROOD.
